UNITED STATES PATENT OFFICE.

HENRY E. MAURER, JR., OF SPRINGFIELD, ILLINOIS, ASSIGNOR TO IDECO, OF SPRINGFIELD, ILLINOIS, A CORPORATION OF ILLINOIS.

LIQUID-DISPENSING APPARATUS.

1,419,284.

Specification of Letters Patent. Patented June 13, 1922.

Application filed March 12, 1920. Serial No. 365,147.

To all whom it may concern:

Be it known that I, HENRY E. MAURER, Jr., citizen of the United States, residing at Springfield, in the county of Sangamon and 5 State of Illinois, have invented a certain new and useful Improvement in Liquid-Dispensing Apparatus, of which the following is a full, clear, concise, and exact description.

My invention relates to liquid dispensing 10 apparatus and has a number of objects and advantages in view.

In my Patent 1,308,091, dated July 1, 1919, I have illustrated a single liquid container and mechanism for filling and emptying the 15 same, the filling apparatus being idle while the contents of the container are being discharged. The equipment disclosed in said patent is primarily of utility in supplying gasolene to the filling tanks of automobiles.

20 It is the general object of my present invention to provide an apparatus employing two containers preferably, though not necessarily, having a single discharge hose and provided with mechanism whereby liquid 25 may be entered into either container while being discharged from the other so that there will be no delay in dispensing the liquid which was hitherto experienced when the apparatus employed but a single container.

30 In the preferred embodiment of the invention, when it is employed in the construction of gasolene dispensing apparatus, each container is in the form of a five gallon capacity inverted glass bottle, the aggregate 35 contents of which would at no time be in excess of five gallons, the limit usually prescribed by fire underwriter associations.

The equipment of my invention will enable all or any part of the contents of either 40 bottle to be withdrawn while a similar quantity is being entered into the other bottle so that all or any portion of the contents of either bottle may be withdrawn while a corresponding quantity is being entered into 45 the other bottle to make the aggregate quantity of liquid in both bottles similar to the quantity contained in either bottle when filled.

In the apparatus of my invention liquid 50 is introduced into the bottles or other containers consequent upon the exhaustion of air from such containers and in order that no liquid may be entered into either container while a corresponding quantity of 55 liquid is not being withdrawn from the other

container, I employ means individual to each container for preventing or permitting exhaustion of air therefrom and controlled by the liquid discharge enabling means individual to the other container to permit air 60 exhaustion upon liquid discharge and to prevent air exhaustion when liquid discharge is prevented.

I will explain my invention more fully by reference to the accompanying drawings 65 showing the preferred embodiment thereof and in which Fig. 1 is a diagrammatic view illustrating the apparatus of my invention in certain adjustment; Figs. 2, 3 and 4 are diagrammatic views illustrating other ad- 70 justments of a part of the apparatus, the views of the valving mechanism being respectively taken on line A—A, B—B, and C—C of Fig. 5 excepting that the angular adjustment of the valving mechanism differs 75 in the different figures; Fig. 5 is a plan view of the valving mechanism; Fig. 6 is a sectional view on line 6—6 of Fig. 5; Fig. 7 is a side view of the valving mechanism shown in Fig. 1; and Fig. 8 is a detail view illustrating another part of the valving structure.

Like parts are indicated by similar characters of reference throughout the different figures.

Each container 1, 1' is desirably in the form of an inverted glass bottle. As I have practiced my invention each bottle is of five gallon capacity. Each bottle neck 3 is received in an annular or tubular seat 4 whose bore is in direct communication with the bore of the bottle neck to afford direct passage for liquid through the bottom of each container (the bottle neck) not only outwardly in the dispensation of the liquid 95 from the container, but also inwardly to replenish the supply of liquid within the container.

The gasolene or other liquid is supplied to the containers from a supply tank 5 which 100 is vented, as at 6. The liquid flows from the tank to the containers through the piping 7 and flows from each container through the eduction nipple 8 and the discharge hose 9 connected with the nipples of both 105 containers. Each container may be drained or emptied back into the tank through the by-pass 10 that connects the passage 3 with the pipe 7, it being desirable to do this when the apparatus is out of service, as at night. 110

A suction-vent tube 11 is preferably within and extends to the top of each container. When liquid is being discharged from either container, the corresponding tube is thrown 5 into communication with the external air to act as a vent. When liquid is being passed into either container, this tube thereof is thrown into communication with the air exhaust pump 12 or the vacuum tank 13 in 10 which vacuum is maintained by said pump.

Each container has a valve 14 individual thereto which serves, according to its adjustment, to seal the inlet-outlet end 3 of the corresponding container, or to establish connection 15 between such container and the discharge hose and then to cut off communication between the supply tank and such container, or to establish connection between such container and the supply tank and then 20 to cut off communication between such container and the discharge hose. Each container has a valve 15 individual thereto which, according to its adjustment, establishes or breaks the continuity of a corresponding by-pass 10. An air valve 16 is 25 individual to each container but is made in one unitary structure with the aforesaid valves individual to the other container, this valve being operated, when liquid is caused 30 to flow from one container, to permit of the exhaustion of air from the other container and allow the introduction of just as much liquid into the latter container as is being discharged from the first container. Each 35 valve 16, according to its adjustment, establishes or breaks connection between the corresponding vent tube 11 and the external air; or establishes and breaks connection between said vent tube and the vacuum tank. 40 The valves 14 and 15 pertaining to each container and the valve 16 individual to the other container are formed in a unitary structure, as shown in Figs. 5, 6 and 7, such unitary structure being preferably a single 45 piece of brass 17 suitably ported to have it form all of the valves, the composite valve 17 operating in a single valve casing 18, that is ported correspondingly to said valve. Each composite valve and its casing are 50 tapered, a spring 19 serving to hold the valve in snug engagement with its casing to avoid leakage. Each of the valves is provided with a handle 20 having a spring pressed 55 plunger detent 21 for holding the handle and valve in the position to which it is adjusted. Each handle sweeps over a dial 22 having notches being positioned at the different places to which each composite valve is to be adjusted to secure the desired control 60 and association of the corresponding container inlet-outlet 3. In Fig. 1 the right hand valve handle is shown at the notch marked "Hose" establishing a valve adjustment that limits the right hand container 1' 65 to connection with the delivery hose 9 and

the external air. When each valve handle is placed at the notch marked "To hold" the valve adjustment shown in Fig. 2 is secured. By this adjustment the corresponding container is shut off from communication with 70 the hose and the supply tank. When the bottle is to be filled the valve handle is placed at the notch marked "To fill bottle" (Fig. 3) and the left hand valve of Fig. 1 to bring the corresponding container opening 75 3 into communication with the supply tank 5 and the upper end of this container into communication with the vacuum tank 13 by way of the tube 11 to exhaust air from the upper end of the bottle to occasion flow 80 of the gasoline or other liquid upwardly into said container from the supply tank. When a bottle is to be drained the corresponding tube 11 is thrown into communication with the external air and the continuity of the by pass 10 is established, 85 whereupon all of the liquid remaining in such container is discharged through the pipe 7 back into the tank 5.

The tube 11 of each bottle is connected 90 with a valve chamber 24. A float 25 is located within each valve chamber and carries a valve 26 for engagement with a seat 27 when connection with the vacuum tank 13 is to be cut off, each valve 26 being separated 95 from its seat when communication between the corresponding container and the vacuum tank is to be established. When a container is about filled a small portion of the liquid will flow downwardly through the tube 11 100 into the valve chamber 24 and when received in sufficient quantity within this chamber the float 25 will rise to engage the valve 26 with its seat 27 whereby communication between the vacuum tank and the container is 105 automatically cut off to cause the cessation of upward flow of liquid from tank 5 into the container. The small portion of liquid remaining in the valve chamber 24 and the corresponding tube 11 at the conclusion of 110 each filling operation is sufficiently sucked back into the corresponding container to lower the float as the liquid comes to its normal upper level, whereby the valve 26 is automatically opened to permit the valve 16 to 115 function.

Fig. 1 well illustrates the valving mechanism of the entire equipment and clearly shows the manner in which the inflow of liquid to either container is absolutely prevented unless the corresponding quantity of liquid is being discharged from the other container. 120

While I have herein shown and particularly described the preferred embodiment of 125 my invention, I do not wish to be limited to the precise details of construction shown as changes may readily be made without departing from the spirit of my invention, but having thus described my invention I claim 130

as new and desire to secure by Letters Patent the following:—

1. Apparatus for dispensing liquid including two liquid containers; eduction piping communicating with said containers and through which liquid may be discharged therefrom; a source of liquid; induction piping connecting said source of liquid with said containers and through which induction piping liquid may be supplied to the containers from said source; vent tubes communicating with the upper portions of the containers; an air pump; and valving means adjustable to connect the vent tube of either container with the external air and the eduction piping with such container to discharge liquid therefrom and to cut off the induction piping from such container and at the same time to cut off the eduction piping from the other container and to connect the vent tube thereof with the air pump and to connect the induction piping therewith to fill such other container.

2. Apparatus for dispensing liquid including two liquid containers; eduction pip-

ing communicating with said containers and through which liquid may be discharged therefrom, this eduction piping having an outlet common to both containers; a source of liquid; induction piping connecting said source of liquid with said containers and through which induction piping liquid may be supplied to the containers from said source; vent tubes communicating with the upper portions of the containers; an air pump; and valving means adjustable to connect the vent tube of either container with the external air and the eduction piping with such container to discharge liquid therefrom and to cut off the induction piping from such container and at the same time to cut off the eduction piping from the other container and to connect the vent tube thereof with the air pump and to connect the induction piping therewith to fill such other container.

In witness whereof, I have hereunto subscribed my name this 8th day of March, A. D., 1920.

HENRY E. MAURER, JR.
